UNITED STATES PATENT OFFICE.

RICHARD WEBB BURNETT, OF MONTREAL, QUEBEC, CANADA.

LOCK FOR DUMP-CAR DOORS.

1,081,204.

Specification of Letters Patent.

Patented Dec. 9, 1913.

Original application filed October 17, 1911, Serial No. 655,253. Divided and this application filed March 25, 1912. Serial No. 686,106.

To all whom it may concern:

Be it known that I, RICHARD WEBB BURNETT, a citizen of the United States of America, residing at the city of Montreal, 5 Province of Quebec, Dominion of Canada, have invented certain new and useful Improvements in Locks for Dump-Car Doors; and I do hereby declare that the following is a full, clear, and exact description thereof.

10 My invention relates particularly to locking mechanism for releasing a gang of doors individually or collectively, and it has for its object to provide a simple and effective means for the purpose.

15 The invention may be said briefly to consist of a series of locking devices adapted to sustain a series of doors in closed position and flexibly connected to a common operating member in order that one or more of 20 the locking devices may be manually operated and their doors released without affecting the other doors of the series.

25 For full comprehension, however, of my invention reference must be had to the accompanying drawings forming a part of this specification in which similar reference characters indicate the same parts, and wherein:

30 Figure 1 is a front elevation of a dump car illustrating a series of doors with my invention applied thereto; Fig. 2 is a similar view with the locking mechanism in the act of releasing all the doors of the series simultaneously; Fig. 3 is a transverse vertical sectional view taken on line A A Fig. 1; Fig. 4 is an enlarged detail elevation of one of the locking devices. Fig. 5 is a horizontal sectional view taken on line A A Fig. 4.

35 40 My invention as above mentioned is adapted for use in locking the discharge doors of dump cars and more particularly the doors controlling the discharge from dump cars having hoppers of the type 45 closed in my pending application filed on October 17, 1911, under Serial No. 655,253, which is shown in the accompanying drawings for purposes of illustration but not 50 specifically described nor claimed as it is covered in the said earlier application.

The hopper floor is indicated at *b* the sides at *c* and the doors at *d* with offset free edges *e*; the latter being disposed in a nearly vertical plane when in service sustaining

comparatively small load and may be comparatively lightly made and consequently do not require more or less complicated closing mechanism but are closed by hand, the only mechanism necessary being for locking them when closed. 55

60 My present invention is confined to the locking mechanism and embodies clamping devices in conjunction therewith. A series of horizontally aligned bars *f* extend lengthwise of the car above and adjacent to the doors, a bar for each door. Each bar has two or more curved presser dogs *g* carried rigidly thereby in bearing relation with the offset edge *e* of the door and a handle or lever *h* by means of which the presser dog 70 is caused to force the door, after having been first closed by hand, into tight bearing relation with the door-frame. Each handle or lever when in clamping position registers between the arms *i* of a bracket *j* 75 riveted to the door, such arms being oppositely recessed to conjointly form a socket for a key *m* suspended by a chain *n*, or other flexible connection, from a shaft *o* rotatably mounted in bearing brackets *p* on the car 80 body, one or both ends of the shaft being squared as at *s* for engagement by a wrench or spanner.

85 In operation no particular skill is needed. The doors are closed by hand, the handles being lifted up to permit it, after the closing of the doors they are clamped to the frame and the operator drops the keys into 90 their sockets. Any door may be opened by knocking out its pin or all the doors may be opened at once by turning the shaft *s* and winding the chains thereon thus removing all the keys simultaneously.

95 I do not claim the specific clamping device illustrated as the same forms the subject-matter of a separate application granted Aug. 12, 1913, under No. 1,069,762 and a divisional part of application Serial No. 655,253, filed October 17, 1911.—

100 What I claim is as follows:—

1. The combination with a car frame and a series of dump doors, of individually manually operative locking devices for the respective doors, an operating member and a series of permanent flexible connections 105 between the individual locking devices and the operating member for the purpose of operating all of the locking devices simul-

taneously and permitting the manual operation thereof individually.

2. The combination with a car frame and a series of dump doors, of a series of clamping handles or levers engaging the doors, brackets upon the doors with which the handles or levers register, keys locking the handles or levers in the brackets, a shaft rotatably mounted upon the car frame, and a

series of flexible connections between the 10 keys and shaft.

In testimony whereof I have signed my name to this specification in the presence of two witnesses.

RICHARD WEBB BURNETT.
